(57) **CLAIM**

The ornamental design for an endoscope shape indicator, as shown and described.

DESCRIPTION

FIG. 1 is a perspective view of an endoscope shape indicator, showing the new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in FIGS. 1-7 depict portions of the endoscope shape indicator and form no part of the claimed design.

The present article is an endoscope shape indicator that, based on a magnetic field detection signal obtained from an endoscope inserted inside a body, performs processing to detect the shape of the endoscope inside the body and display the shape at a monitor.
